UNITED STATES PATENT OFFICE.

HARRY VOLIS, OF DETROIT, MICHIGAN.

GAUGE.

1,417,001.

Specification of Letters Patent. Patented May 23, 1922.

Application filed March 14, 1921. Serial No. 452,122.

To all whom it may concern:

Be it known that I, HARRY VOLIS, a citizen of the United States, and residing at Detroit, in the county of Wayne and State of Michigan, have invented a new and Improved Gauge, of which the following is a specification.

This invention relates to gauges for accurately determining the interior diameters of cylindrical holes and the distances between opposed surfaces, and its object is to provide a measuring instrument of this character which shall be simple in construction, which shall not be liable to get out of order, and which shall be accurate.

This invention consists of a body provided with any desired number of longitudinal slots, a blade slideable in each slot, a shaft rotatable in the body, and means actuated by the shaft and engaging the blades whereby the blades may be moved outwardly when the shaft is turned in one direction, and resilient means for moving the blades inwardly when the shaft is turned in the opposite direction.

It further consists of graduated members attached to the shaft and to the body whereby the number of rotations and the angles of rotations may be indicated.

It also consists in the details of construction illustrated in the accompanying drawing and particularly pointed out in the claims.

In the accompanying drawing, Fig. 1 is an elevation of this improved gauge. Fig. 2 is a section on the line 2-2 of Fig. 1. Figs. 3, 4 and 5 are sections on the lines 3-3, 4-4 and 5-5 of Fig. 2. Fig. 6 is a perspective of one of the blades. Fig. 7 is a perspective of an auxiliary gauge bar.

Similar reference characters refer to like parts throughout the several views.

The body 1 of this gauge is preferably cylindrical and is formed with any desired number of radial slots in which the blades 2 are mounted. These blades are preferably opposite to each other in order that their outside measurements may be checked by means of ordinary micrometer calipers. Each of these blades is preferably U-shaped in cross section and its parallel sides are formed with the inclines 3 to be hereafter described.

Within the blades are springs preferably formed of the leaves 4, 5 and 6, one of which has inclined projecting ends 7 which are

adapted to engage the shoulders 8 formed in the body at the inner ends of the radial slots. Attached to the outer end of the body is a disk 10 which is also formed with the shoulders 8 which are engaged by these projecting ends 7 of the springs. While this plate may be attached to the body in any desired manner, I prefer to use screws 12.

The body has a tubular extension 13 in which is journaled a shaft 14 whose outer end 15 is also journaled in the disk 10, and this shaft is formed with two groups of threads 16 and 17 which are of reversed pitches. Mounted on each one of these groups of threads is a head 18 internally threaded to fit the threads of the shaft 14 and provided with radial projections 19 having inclined outer surfaces adapted to engage the inclined surfaces 3 of the blades 2.

It will be noticed that when this shaft 14 is turned in one direction the heads 18 will be separated and the inclined surfaces of the projections 19 will slide on the inclined surfaces 3 of the blades 2 and thereby move these blades radially outwardly. In doing so the springs within the blades will be flexed, their ends 7 engaging the shoulders 8 as before stated, and so when the shaft is turned in the opposite direction these springs will force the blades inwardly. When the parts are accurately made these blades will move outwardly in such a manner that their outer surfaces will always remain parallel to the axis of the shaft and the outside measurements at both ends of opposed blades will be the same.

The tubular extension 13 is formed with threaded portions 21 and 22. A tubular handle 23 is screw-threaded on the portion 21 and a sleeve 24 is screwed onto the threaded portion 22 of the extension. When this sleeve is turned on the tubular extension the graduations 27, seen through the window 26 in the handle 23 (Fig. 1) pass the line 25 on the tubular extension 13 and at the same time the sleeve moves longitudinally of the graduations adjacent this line 25. The pitch of the threads 16 and 17 is preferably the same as the pitch of the threaded portion 22 of the tubular extension and of the sleeve 24 and this pitch is indicated by the graduations on the tubular extension 13 adjacent the line 25, so that the inner edge of the sleeve 24 will move longitudinally of the

tubular extension the distance between graduation lines thereon for each rotation, and the angular distance that this sleeve is rotated will be indicated by the graduations 27 5 thereon.

I also form internal threads in the end of this tubular extension 13 and screw a small hollow plug 31 into this extension. The inner end of this plug holds a ball bearing 32 10 against a shoulder 33 on the shaft 14, although it will be understood that this ball bearing may be omitted. The outer portion 34 of this shaft may be threaded to receive a sleeve 35 which positions a second ball 15 bearing 36, slideable on the shaft, so that when this sleeve 35 has been properly adjusted the shaft 14 will be absolutely prevented from moving endwise any appreciable amount.

20 In order to turn the shaft I have mounted a knob 40 on the end of the handle 23, holding it in position by means of a flange 41 on the handle. This knob screws onto a threaded end 42 on a forked member 43 25 which is seen in end elevation in Fig. 3, and extending into the slot 44 in this forked member is a block 45 which may be secured to the shaft and to the sleeve 35 by means of a pin 46 or in any other desired manner.

30 When the knob 40 is turned this forked member 43 will turn with it and rotate the shaft through this block 45. The rear end 47 of the sleeve 24 is similarly forked; in fact, the same view will be had when looking in either direction from the line 3—3 of Fig. 2. The forked end 47 of the sleeve 24 receives this block 45, and the sleeve is therefore rotated by means of this block whenever the knob 40 is turned and the 40 sleeve may travel along this block because of the threads on the end of the tubular member.

It will therefore be seen that the blades 2 may be moved freely inwardly and outwardly by simply turning the knob 40 and that the endwise movement of the shaft is prevented, but the endwise movement of the sleeve 24 is not interfered with, so that the 45 graduations which are read through the window 26 always correctly indicate the outside measurements of this instrument.

It will be understood that the number of these blades may be varied to meet the various requirements and that the details and 50 proportions of the various parts of this instrument may be changed by those skilled in the art without departing from the spirit of my invention as set forth in the claims.

When this instrument is to be used for 60 measuring threads an auxiliary bar 50 provided with threads 51 and pins 52 may be mounted on the blades 2, which in that case are provided with small holes 53 to receive these pins. Any other desired type of auxiliary bars may be employed and when smooth 65

bars are employed, the range of measurements capable of being performed by an instrument of this character may be greatly increased so that one instrument may be used for measurements between considerable 70 limits.

I claim:

1. In a gauge, the combination of a hollow cylindrical body having a radial slot, a shaft rotatably mounted in the body and 75 having two groups of threads, heads threaded on said threaded portions and having projections inclined to the axis of the shaft registering with said radial slot, a blade mounted in the slot and having inclined surfaces engaging the inclined projections on the heads whereby the blade is forced outwardly when the shaft is turned in one direction, and a spring to force the blade inwardly when the heads are moved in the 80 opposite direction.

2. In a gauge, the combination of a hollow cylindrical body having a radial slot, a central shaft in the body having two oppositely threaded portions, heads threaded on the 90 shaft and having projections inclined to the axis of the shaft, a blade mounted in the slot and provided with two oppositely inclined surfaces adapted to engage said inclined projections on the heads, there being a scale 95 extending longitudinally of the shaft to indicate the number of rotations of the shaft, and a sleeve co-acting with the scale and movable longitudinally of the shaft to indicate the degrees through which the shaft is 100 rotated.

3. In a gauge, the combination of a hollow body having a tubular extension and oppositely disposed slots, a shaft mounted in the body, blades slidably mounted in the 105 slots, means engaging the shaft and the blades whereby the blades are moved outwardly when the shaft is turned, the end of the tubular extension being graduated, and a graduated sleeve rotatable with the 110 shaft and co-acting with and extending over the graduated portion of the tubular extension whereby the number and portions of the rotations of the shaft are indicated.

4. In a gauge, the combination of a hollow body having a tubular extension and oppositely disposed slots, a shaft mounted in the body, blades slidably mounted in the slots, means engaging the shaft and the blades whereby the blades are moved outwardly when the shaft is turned, the end of the tubular extension being graduated, a graduated sleeve rotatable with the shaft and extending over the graduated portion of the tubular extension whereby the number and portions of the rotations of the shaft are indicated, a tubular handle extending from said body and enclosing the tubular extension and the sleeve theron, and a knob connected to the shaft and rotatable in the 125 130

outer end of the handle whereby the shaft may be turned.

5. In a gauge, the combination of a hollow body having a tubular extension and oppositely disposed slots, a shaft mounted in the body, blades slidably mounted in the slots, means engaging the shaft and the blades whereby the blades are moved outwardly when the shaft is turned, the end of the 10 tubular extension being graduated, a graduated sleeve rotatable with the shaft and extending over the graduated portion of the tubular extension whereby the number and portions of the rotations of the shaft are indicated, a tubular handle extending from said body and enclosing the tubular extension and the sleeve thereon, a knob rotatable in the outer end of the handle whereby the 15 shaft may be turned, and a slidable connection between the sleeve and shaft whereby 20

the sleeve may be permitted to move longitudinally of the shaft while being turned thereby.

6. In a gauge, the combination of a hollow body having a tubular extension and oppositely disposed slots, a shaft mounted in the body, blades slidably mounted in the slots, means engaging the shaft and the blades whereby the blades are moved outwardly when the shaft is turned, the end of the 25 tubular extension being graduated, a graduated sleeve rotatable with the shaft and extending over the graduated portion of the tubular extension whereby the number and portions of the rotations of the 30 shaft are indicated, and adjustable means mounted in the tubular extension whereby the shaft is prevented from moving longitudinally in said body. 35

HARRY VOLIS.
